(57) **CLAIM**

The ornamental design for a gaming die as shown and described.

DESCRIPTION

FIG. 1 is a perspective view of a gaming die showing my new design;

FIG. 2 is a top plan view thereof;

FIG. 3 is a left side elevational view thereof;

FIG. 4 is a right side elevation view thereof;

FIG. 5 is a bottom plan view thereof;

FIG. 6 is a front elevational view thereof, the undisclosed opposite side being identical;

FIG. 7 is a perspective view of a second embodiment of FIG. 1;

FIG. 8 is a top plan view of FIG. 7;

FIG. 9 is a perspective view of a third embodiment of FIG. 1

FIG. 10 is a top plan view of FIG. 9;

FIG. 11 is a left side elevational view of FIG. 9;

FIG. 12 is a right side elevational view of FIG. 9; and,

FIG. 13 is a bottom plan view of FIG. 9.

The undisclosed sides of the second embodiment are identical to the first embodiment.

The undisclosed sides of the third embodiment are identical to the first embodiment.
